[57] CLAIM

The ornamental design for a bottle, as shown and described.

DESCRIPTION

FIG. 1 is a front elevation of a bottle showing my new design;

FIG. 2 is a left side elevation thereof;

FIG. 3 is a rear elevation thereof;

FIG. 4 is a right side elevation thereof;

FIG. 5 is a top plan view thereof;

FIG. 6 is a bottom plan view thereof; and,

FIG. 7 is a bottom plan view of a second embodiment of the bottle.

The broken line showing of a cap is for illustrative purposes only and forms no part of the claimed design.

FIG. 2

FIG. 1

FIG. 3

FIG. 7

FIG. 4

FIG. 5

FIG. 6
